ICE SKATING SHOE

Samuel Wold, Chicago, Ill., assignor to Alfred Johnson, Chicago, Ill.

Application May 5, 1938, Serial No. 206,114

1 Claim. (Cl. 36—2.5)

This invention relates to skating shoes in general and particularly to an ice skating shoe whereby the ice skates are permanently fastened to the shoes.

The primary object of the present invention is to provide an ice skating shoe with a reinforcement to maintain the shoe in proper position with respect to the skate during all positions of the skate on the ice; to prevent the counter of the shoe from bending, becoming permanently displaced or becoming weak or bulgy; to reinforce the connection between the shoe and the skate whereby the shoe will remain in proper position with respect to the heel plate of the skate and prevent the shoe from deforming laterally during use; to provide a reinforcement in the shoe with respect to the skate so as considerably to reduce deterioration of the joints and stitches due to continuous wetting and drying of the skate during use; to rigidly support the shoe with respect to the skate but at the same time permit a sufficient amount of flexibility, which a good skate shoe should have.

Numerous other objects and advantages will be apparent throughout the progress of the following specification.

The accompanying drawing illustrates a selected embodiment of the invention and the views therein are as follows:

Fig. 1 is a detail elevational view of a shoe, parts being broken away for the sake of clearness;

Fig. 2 is a vertical sectional view on the line 2—2 of Fig. 1;

Fig. 3 is a top plan view of the improved strengthening member;

Fig. 4 is a detail perspective view thereof; and

Fig. 5 is a detail sectional view on the line 5—5 of Figs. 3 and 4.

The combined ice skate and shoe herein shown for the purpose of illustrating the invention comprises a skate 10 upon which there is rigidly mounted a shoe 11. The skate 10 comprises the longitudinal tubular portion 12 to which the runner 13 is rigidly fastened. A tubular portion 14 is attached to the tube 12 and rigidly supports a sole plate 15 upon which the sole of the shoe is fastened. A rear tube 16 is also fixed to the tube 12 and carries a heel plate 17 which supports the heel structure of the shoe 11. The tube 16 is higher than the tube 14 so as to maintain the heel portion of the shoe at a higher elevation than the sole portion as is customary in all shoes, the tubular section 16 taking the place of the conventional leather heel in ordinary walking shoes, thereby maintaining the proper relation-

ship in the ice skating shoe as regards the heeled walking shoe.

The shoe 11 comprises a sole portion 18 which extends continuously from the toe of the shoe to the end of the heel in the usual manner, as clearly shown in Fig. 1. The body portion or sides 19 of the shoe extend inwardly and are arranged on top of the sole 18, as indicated at 20, being reduced at 21 so as to eliminate bulkiness inside of the shoe. The counter 22 of the shoe extends inwardly on top of the inturned edge 20 of the side portions, as indicated at 23, also being reduced in thickness to a thin edge, as indicated at 24. An inner sole 25 is arranged on top of the inturned portions 20 and 23 of the outer portion and counter. In conventional ice shoes it has been the practice to pass rivets through the metal plate 17, the outer sole 18, and the inner sole 25 to maintain the parts in position. However, it has been found that this conventional arrangement is insufficient to stand the abuses to which ice skating shoes are subjected, and therefore the present invention contemplates the use of a strengthening member 26 to render the skate and shoe more rigid but at the same time permitting the flexibility required.

The reinforcing member comprises a heel portion 27 which is thinner at its inner edge 28 and increases in thickness toward the rear, as indicated at 29, there being an integral upstanding flange 30 which decreases in thickness from its juncture 31 to its upper edge 32. This reinforcing member 26 is arranged inside of the shoe and rests upon the upper surface of the sole 25, as clearly shown in Fig. 2.

Rivets 33 pass through the metal heel plate 17, the outer sole 18, the portions 20 and 23 of the shoe sides and counter, respectively, and also through the base portion 29 of the reinforcing member 26. Other fastening or supporting means, such as stitching 34, also pass through all the aforementioned parts with the exception of the metal heel plate 17. The rivets 33 have their upper surfaces 35 properly clinched and pressed into the leather body 29 of the reinforcing member 26 so as to be smooth on the inside of the shoe. Stitching 36 passes through the outer body 19 of the shoe, the counter 22, and the upstanding flange 30 of the reinforcing member 26, and, inasmuch as the reinforcing side soles 30 taper to a relatively sharp point 32, there is no bulkiness or corners or sharp edges to bother the feet of the wearer.

It has been found in actual practice that the fastening of a reinforcing member inside of an

ice skating shoe in the manner herein taught considerably strengthens the shoe, gives the shoe longer life, and causes the shoe to be more rigidly attached to the skate, but at the same time allows 5 a certain amount of flexibility. The reinforcing member may be cemented, sewed, stapled, riveted, or otherwise secured to the inside of the shoe to reinforce the insoles, outsoles and counters at the most critical point of the shoe. The reinforcing member is particularly desirable in a shoe 10 which requires strength and durability in the counters.

It has been found that by using metal wire for the stitching 36 the life of the shoe has been 15 considerably enhanced and increased over the use of non-metal stitches because non-metal stitching would deteriorate in use because of the alternate and continuous wetting and drying to which the shoe is subjected during use.

20 The invention, therefore, provides means for reinforcing and rigidly fastening a shoe to a skate, and reducing deterioration to a considerable extent without in any way affecting the comfort of the skate. In fact, the addition of 25 the reinforcing member as well as reinforcing the shoe adds additional comfort to the shoe, not only because of the comfort provided but because it prevents the shoe from shifting in an angular position during the skating stride.

30 By the term "leather," as employed herein, is included artificial and imitation leather having the general properties of leather for use in the present art.

Changes may be made in the form, construction and arrangement of the parts without departing from the spirit of the invention or sacrificing any of its advantages and the right is hereby reserved to make all such changes as fairly 5 fall within the scope of the following claim.

The invention is hereby claimed as follows:

A skating shoe and attached skate construction comprising a heel plate for the skate, an outer sole for the shoe, an inner shoe sole arranged above the outer sole, a shoe body, a counter, the counter and shoe body having their lower edges contacting and arranged between the inner and outer soles, a reinforcing member mounted within the heel portion of the shoe and 10 upon the inner sole and comprising a unitary continuous leather heel receiving sheath having a continuous lower wall disposed upon the upper surface of the inner sole, continuous, integral, upwardly extending flange portions formed about 15 the sides and rear of said lower wall, said reinforcing member being located completely interiorly of said inner sole and counter, spaced rows of fastening means extending through the body portion, the counter and the flange of the 20 reinforcing member at the sides thereof, adjacent the sole portion, and fastening means extending through said heel plate, said inner sole, said outer sole and the lower wall of said reinforcing member and permanently holding 25 30 said members in associated relationship.

SAMUEL WOLD.
